SHIPPING CASE

Lloyd G. Clark and Merrill A. Grogel, Grand
Rapids, Mich., assignors to American Box
Board Company, Grand Rapids, Mich., a cor-
poration of Michigan

Application August 10, 1936, Serial No. 95,158

7 Claims. (Cl. 229—37)

This invention relates to a shipping case which is designed to be made from paper board or fiberboard. Shipping cases of our invention are to receive and carry relatively heavy merchandise, such as bottled goods and, therefore, require particularly that they be of a strong and durable character and fully capable of withstanding the strains to which subjected in use. Our invention has for one of its objects the provision of a very novel construction of bottom for the case which is of great strength and which can be produced very readily and economically.

In conjunction with shipping cases of this character, the bottom structure which we have devised is of utility irrespective of the particular top closure which is used. With certain types of bottled goods, such as beer, it is very desirable that the light be excluded, and our invention has for another object and purpose the provision of a novel character of top closure and end structure whereby the ends of the case are strengthened and the necessary hand holes for carrying the case are covered to exclude light, yet such hand holes may be used with substantially as great ease as though not thus covered.

A further object of the invention is to provide a novel structure of shipping case having both the bottom closure and end structure advantages stated, made from a single piece of paper or fiberboard, which can be shipped in a flat condition and set up at its destination in a very simple and practical manner and with the use of a minimum of fastening staples and of stapling machinery. Further, the amount of waste in conjunction with the paper or fiberboard stock from which the blanks are cut is reduced to a minimum; and because of the flat character of the blank, all in one continuous piece, from which each shipping case is made, there results a desirable facility in printing advertising data or the like upon selected outer sides of the case.

These and many other advantages not at this time specifically stated will appear upon an understanding of the invention from the following description, taken in connection with the accompanying drawings, in which,

Fig. 1 is a plan of the shipping case blank from which the completed case is made.

Fig. 2 is a horizontal section through the shipping case of our invention, substantially on the plane of line 2—2 of Fig. 3.

Fig. 3 is a longitudinal vertical section substantially on the plane of line 3—3 of Fig. 2.

Fig. 4 is a transverse vertical section substantially on the plane of line 4—4 of Fig. 2, and

Fig. 5 is a perspective view looking into the shipping case after the same has been cut transversely, substantially on the plane of line 4—4 of Fig. 2.

Like reference characters refer to like parts in the different figures of the drawings, and the sections taken are in the directions indicated by the arrows.

The shipping case which, preferably, is made from paper or fiberboard is produced initially in a flat blank, shown in Fig. 1, longitudinally of which and at its central portion, are the side 1, end 2, opposite side 3 and opposite end 4 in longitudinal alignment. At the free end of the side 1 there is a flap 5 and the blank is creased transversely as indicated by parallel lines 6 the full width of the shipping case blank. Similarly between the side 1 and end 2 are like creases 7; 20 between the end 2 and the side 3, creases 8; and between the side 3 and the end 4, creases 9. When the blank is folded about the creases 6, 7, 8 and 9, the sides 1 and 3 and the ends 2 and 4 are disposed parallel to each other and the flap 5 may be bent within the outer edge portion of the end 4 and stapled thereto.

Alongside the bottom edges of the sides and ends 1, 2, 3 and 4 are the bottom members of the shipping case. The section 10 extends from the lower edge of the side 1, section 11 from the lower edge of the end 2, 12 from the lower edge of the side 3 and 13 from the lower edge of the end 4. A notch 15 is cut in the blank to define one end of the flap 5 previously described and also a flap 14 which extends from the outer end of the section 10, the same creasing 6 being utilized for easy folding of the flap 14 as are used with the flap 5. The blank is creased longitudinally as at 16 to provide the division between the sides and ends of the box and the bottom members. The blank is cut on the lines 17 and 19 to provide flaps 18 at the ends of the sections 10 and 12, similar in all respects to the flap 14, and in both of the sections 11 and 13, 45 the material extends beyond the edges of the sections 10 and 12 in the form shown, providing tongues 20 which may be folded about the creases 7, 8, 9 and 9a. The section 13 at the end edge of the blank is cut on the lines 17a and 19a 50 to make the part 13 symmetrical and identical in form with the part 11.

When the case is set up the bottom sections 10 and 12 are turned inwardly from the lower edges of the opposite sides 1 and 3, the free outer edges 55

of the bottom sections 10 and 12 coming together as shown in Figs. 4 and 5. The parts 11 and 13 are likewise turned inwardly from the lower edges of the ends 2 and 4 lying over the bottom sections 10 and 12. The various flaps 14 and 18 at the ends of the bottom sections 10 and 12 are turned upwardly at the outer sides of the ends 2 and 4 and are stapled thereto. The tongues 20 will be disposed at the inner sides of the sides 1 and 3 at the middle portions thereof and are turned upwardly, as best shown in Fig. 5 and, may be stapled to the adjacent sides 1 and 3. It is not absolutely necessary that these tongues be stapled but in many cases it is desirable and the structure lends itself perfectly to such stapling.

It is evident from the foregoing description that a very strong reinforced bottom structure is provided. There is not only a double thickness of material but in a zone midway between the ends of the case the connection of the tongues 20 to the sides provides an exceedingly strong reinforcement which resists any tendency of the bottom to bulge or give, not only from the weight of the contents within the case, but due to any sudden lifting of the case which puts an additional strain upon the bottom.

The upper and closure structure for the shipping case lies in the blank at the opposite side of the sides and ends 1, 2, 3 and 4, longitudinal creases 21 defining the folding lines. A top closure section 22 joins with the upper edge of the side 1. A section 23, to be folded downwardly within the end 2, joins with the upper edge thereof. A second top closure section 24 is joined at the upper edge of the side 3 and a second downwardly and inwardly folding member 25 joins with the upper edge of the end 4, all having the equivalent of a hinged connection to said respective sides and ends on the creased lines 21. The top closure section 22 has a flap 26 in alignment with and in the same plane with the flap 5 and foldable about the creases 6, and with a notch 27 at the outer edge cut inwardly between the creased lines 6, thereby providing a tongue 28 which is substantially square in cross-section. The tongue 28 is foldable at right-angles to the plane of flap 26 about creases 29 which extend the full length of the blank. The creases 29 divide the top section 22 from a projecting flange 30. At the inner end of the section 22 a like flap 26, notch 27 and tongue 28 are made by cutting the part 23 on the lines 31 and 32. Similarly the other top section 24 has end flaps 26 with tongues 28 provided by notches 27, there being a flange 33 projecting from the top section 24 similar to the flange 30; and the members 23 and 25 are cut on the lines 31 and 32 and 31a and 32a as shown to provide the structure described.

The ends 2 and 4 of the shipping case each have a longitudinal slot 34 with closed ends cut therethrough for the entrance of the hands in lifting and carrying the case. Directly above each slot 34 is a vertical slot 35 with closed ends across which the creases 21 pass midway between the ends of said slots 35. Above each of the slots 35 in each of the members 23 and 25 a hand hole closing flap 36 is cut, the cut being at three sides, the remaining side being integral with the fiber or paper board material and substantially at the creases 29.

With a structure as described, the flaps 26 are turned inwardly at right-angles along the creased lines 6, 7, 8 and 9, the tongues 28 are then turned inwardly at right-angles to the flaps 26, after which the flanges 30 and 33 are bent inwardly at

right-angles to the top sections 22 and 24, the ends of said flanges and the tongues 28 being stapled together. The parts 23 and 25 are turned inwardly about the creased lines 21 so as to lie flat against the inner sides of the ends 2 and 4, as shown in Fig. 3. In such position the upper free edge portions of the closures 36 cover the openings 34. The cover sections may be turned to closed position with the ends of the flanges 30 and 33, to which are connected the tongues 28, received within the open upper ends of the slots 35. That is, when the parts 23 and 25 are turned to the position illustrated in Fig. 3, the slotted portions at 35 are in effect doubled about the mid points of the slots, thereby providing at the upper edge of each end of the box an open slot to receive the flanges of the cover sections. It is evident, as illustrated in Fig. 3, that the hand hole openings 34, covered by the parts 36 have any light which would otherwise pass therethrough excluded, but that the flaps 36, will turn readily inward to permit entrance of the fingers in handling the shipping case.

The top structure described is very practical and satisfactory in use. The top of the case is strongly reinforced, the ends of the casings are reinforced, light is excluded and the entire case, including the bottom structure previously described, is of a very strong character. The blanks for the boxes occupy little space in transportation. There is comparatively little stapling to be done to set up the case when it reaches its destination. The flap 5 is stapled to the end 4, the flaps 14 and 18 are stapled to the ends 2 and 4, if desired the tongues 20 are stapled to the sides 1 and 3 and the tongues 28 are stapled to the ends of the flanges 30 and 33. One staple only is required for each of the tongues 28, two staples for each of the flaps 14 and 18 and preferably five for connecting the flap 5 to the end 4, though four staples may be used very satisfactorily for the flap 5. Sixteen staples therefore are all that are required for complete fastening the various parts together. This reduces materially the number of staples which has previously been required in shipping cases designed to serve similar purposes.

The invention is defined in the appended claims and is to be considered comprehensive of all forms of structure coming within their scope.

We claim:

1. A shipping case having vertical sides and ends connected together at the corners of said case, bottom sections hinged to the lower edges of said sides and extending inwardly toward each other and meeting at substantially the longitudinal central plane of the case, auxiliary sections hinged to the lower edges of said ends and extending inwardly therefrom over said bottom sections and meeting substantially at the central transverse plane of the case, each of said auxiliary sections at each side thereof adjacent thereto adapted to be turned upwardly at the inner sides of the sides of the case, as specified.

2. A shipping case having vertical sides and ends connected together, bottom sections hinged to the lower edges of said sides extending horizontally inward toward each other and meeting at their free longitudinal edges, means for securing said bottom sections to the ends of the case, auxiliary sections hinged to the lower edges of said ends and extending inwardly toward each other and substantially meeting at their free end

edges, and means for securing said auxiliary bottom sections to the sides of the case.

3. A shipping case having vertical sides and ends, and a horizontal bottom, and sections hingedly connected to the upper edges of the ends of said case and extending downwardly at the inner sides of said ends, each of said ends having an opening for hand insertion therethrough, and each of said sections including an integral flap in the body of the section severed from said section at its upper and vertical edges and hinged to the section at its lower edge, said flaps being adapted to cover the adjacent openings in the ends of the case.

15 4. A blank of paper or fibreboard creased longitudinally and transversely to define two sides and two ends for the case lying in alignment longitudinally of the blank with bottom sections extending from the lower edges of said sides and auxiliary sections extending from the lower sections of said ends, said blank being cut to provide a flap at each end of one of said bottom sections and at one end of the other bottom section, said flaps being cut from the material of 25 said auxiliary sections, and an additional flap at the opposite end of said last-mentioned bottom section and at the same end of the adjacent side of the case, whereby said blank may be folded to provide vertical sides and ends, the last-mentioned flap being secured to one of said ends, said bottom sections turned inwardly toward each other and the flaps at the ends thereof secured to the ends of the case and the auxiliary sections turned inwardly toward each other to lie along- 30 side of the bottom sections.

35 5. A shipping case having parallel spaced-apart vertical sides and parallel spaced-apart vertical ends connected together at vertical corners of the case, bottom sections having flaps at each end thereof hinged one at the lower edge of each side of the case to be turned in horizontally and with the flaps turned upwardly and connected to the lower parts of the ends of the case, auxiliary reinforcing sections for the bottom hingedly 40 connected to the lower edges of the ends and turned inwardly to lie adjacent the bottom sections, and means at the ends of said reinforce- 45

ing sections for connecting the same to the shipping case at points near the transverse middle plane of said case.

6. A shipping case comprising, vertical sides and ends connected together at the corners thereof, bottom sections of greater length than the sides hinged to the lower edges of said sides and extending inwardly toward each other, the end portions of said bottom sections providing flaps turned upwardly at their ends and connected to the lower portions of the ends of the case, and inwardly extending auxiliary sections hinged at the lower edges of said ends extending inwardly therefrom over said bottom sections, the free edges of said bottom sections meeting substantially at the central longitudinal plane of the case, and the free edges of said auxiliary sections meeting substantially at the central transverse plane of the case, additional sections hingedly connected with the upper edges of said ends and turned downwardly at the inner sides of the ends, each of said ends having an opening therethrough covered by the last-mentioned sections, said last-mentioned sections having a flap cut therefrom at three edges and hinged at its lower edge whereby the same may be moved inwardly, as and for the purposes described.

7. A shipping case having vertical, spaced-apart sides and ends connected together at their corners, bottom sections hinged to the lower edges of said sides extending inwardly toward each other and meeting at their free edges, flaps at the ends of said bottom sections hinged thereto and turned upwardly to lie against the lower portions of said ends, means securing said flaps to the ends, auxiliary sections hinged to the lower edges of said ends and turned inwardly and lying over the bottom sections and substantially meeting at their free end edges, as specified, each of said auxiliary sections at each side thereof and adjacent its free end edge portion having an integral tongue hinged thereto and turned upwardly to lie against the inner side of each side of the case, and means securing said tongues to said 40 sides of the case.
